(57) CLAIM

The ornamental design for a car seat extender for dogs as shown and described.

DESCRIPTION

FIG. 1 is a perspective view of a car seat extender for dogs showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the car seat extender for dogs where the car seat extender for dogs is in a configuration of use.

The long-thick evenly spaced broken lines in the drawings depict stitching and form no part of the claimed design. The short-thin evenly spaced broken lines in the drawings depict portions of car seat extender for dogs and form no part of the claimed design.
